[57] CLAIM

The ornamental design for a cube stand, as shown and described.

DESCRIPTION

FIG. 1 is a top perspective view of my design invention;
FIG. 2 is a bottom perspective view thereof;
FIG. 3 is a top plan view thereof;
FIG. 4 is a bottom plan view thereof; and,
FIG. 5 is a typical side elevational view, the broken lines
being for environmental purposes only and form no part of
the claimed design.
